[57] CLAIM

The ornamental design for a combined display container and packaging insert, substantially as shown.

DESCRIPTION

FIG. 1 is a front perspective view of a combined display container and packaging insert showing my new design; FIG. 2 is a front perspective view thereof in an opened condition;

FIG. 3 is a front elevational view thereof;

FIG. 4 is a rear elevational view thereof;

FIG. 5 is a side elevational view, the opposite side being substantially a mirror image thereof;

FIG. 6 is a top plan view thereof;

FIG. 7 is a top plan view of the packaging insert on an enlarged scale; and

FIG. 8 is an elevational view thereof.
